JEWELRY STRUCTURE

Karl Fassnacht, Cranston, R. I., assignor to
Speidel Corporation, Providence, R. I., a corpora-
tion of Rhode Island

Application May 12, 1938, Serial No. 207,479

5 Claims. (Cl. 63—23)

This invention relates to a jewelry structure, such as a bracelet or the like, including an ornamental device adapted for use as a charm or jewelry ornament, which may be suspended from a chain, pin or bracelet and serve as an auxiliary to a chain or bracelet structure.

One object of the invention is the provision of a jewelry structure of this character comprising a plurality of ornamental devices and forming an ornamental bracelet structure.

A further object of the invention is the provision of an ornamental device of this character formed of separate parts, each capable of being readily constructed as separate elements and which may be easily assembled to provide a finished article which is inexpensive to manufacture.

Another object of the invention is the provision of an ornament formed to simulate a cigarette package, and which is made up of separately constructed elements capable of being readily assembled and adapted to interfit with each other to present the appearance of being of integral construction throughout.

Other objects and advantages of the invention relate to various improved details of construction and novel arrangements of the parts as will be more fully set forth in the detailed description to follow:

30 Referring to the drawing:—

Fig. 1 is a plan view showing a portion of a bracelet chain having one or more ornamental devices suspended therefrom.

Fig. 2 is an enlarged perspective view of the ornament showing the same in such position that a portion of the cigarette simulating element is partially projected.

Fig. 3 is an enlarged view of the ornament showing one side thereof removed and illustrating the form and location of the elements housed within the tubular shell of the ornament.

Fig. 4 is a perspective view of the internal frame and cigarette simulating member showing the same in slightly separated relation and in substantially their normal positions, removed from the tubular outer frame portion of the ornament, and,

Fig. 5 is a detail sectional view through the end section 16 showing the shape of the end extensions 24, taken substantially along the line 5—5 of Fig. 3.

In the embodiment of the invention illustrated herewith 1 designates a bracelet chain such as may be formed of separate links suitably joined together and which may be of any suitable or

desired character to provide an ornamental chain structure. The bracelet chain 1 is provided at one end with an open link or loop member 2, to which may be secured a latch link 3 of suitable character carried by the opposite end of the bracelet chain.

A plurality of ornamental devices 5 may be supported from and carried by the bracelet chain 1 through attaching links 6 carried by or forming a part of the bracelet chain. These ornamental devices or structures 5 may be of rectangular shape and so formed as to simulate a cigarette package of any desired or well-known brand. Each of the ornamental devices may also be provided with a cigarette simulating element or elements capable of and adapted to project from one end of the ornament to give the appearance of a partially open cigarette package from which a portion of the contents are projected.

Each of the ornamental devices 5 may comprise an open ended tubular portion 8, which is in the form of a rectangular tube and which may be formed from any suitable or desired material, such as metal, and be capable of being plated with precious metal or embossed or ornamented to present the appearance of any desired form of cigarette package.

The tubular portion 8 is provided with a lateral opening 9 adjacent to one end to provide means whereby the ornament 5 may be secured to the chain 1 by means of the attaching link 6. The tubular portion 8 may be shaped to comprise oppositely positioned relatively narrow side faces 10, and oppositely positioned relatively wide side faces 11, one or both of which side faces 11 may be embossed, enameled or otherwise decorated to simulate the appearance of any desired form of cigarette package.

A frame member 14 which comprises a base 15, an upright end 16 located adjacent one extremity thereof and an upright end 17 adjacent the other extremity together with a side 18 substantially parallel with the base 15, is shaped to fit within the open ended tubular portion 8 in such a manner that the upright end 16 will fit closely within and form a substantially complete closure for one end of the tubular member 8, while the upright end 17 fits within and forms a partial end closure for the opposite end of the tubular member 8 when the parts are in assembled position.

A cigarette simulating element 20 which may be of substantially rectangular form, is adapted to be mounted on the side 18 of the frame member 14 and is provided with a lateral projection 21 which fits slidably within a slot 22 formed in

- the side 18 to allow the cigarette simulating element 20 to slide to a limited extent longitudinally of the side 18 whereby its end portion may be projected outwardly to a limited extent through the end opening of the tubular member 8, while at the same time the pin and slot connection 21—22 serves to prevent the complete removal of the cigarette simulating element 20 from the tubular member.
- 10 The free end portion of the side 18 of the frame member is cut away to form opposed edge extensions 24 adapted to fit within edge recesses 25 cut in the upright end 16, which edge extensions 24 may be undercut to grip engaging portions of the end member 16 and hold the parts of the frame member 14 securely in position relative to each other when positioned within the hollow tubular member 8.
- 15 The frame member 14 is provided with spaced openings 26 and 27 formed in the base 15 and end portion 17 which are separated by a bridge 28. When the parts are assembled the ring 6 is passed through the openings 26 and 27 and the opening 9 in the tubular member 8 to embrace the bridge 28, thereby holding the frame 14 from sliding movement relative to the tubular member 8, so that the parts of the ornament are secured firmly against separation.

What I claim is:

- 30 1. An ornamental charm for bracelets or the like in simulation of a cigarette package comprising, a rectangular tubular member, a frame slidably mounted within said tubular member and having a portion serving as a closure for one end of said tubular member, and a cigarette simulating element mounted in said tubular member and supported by said frame.
- 35 2. An ornamental charm for bracelets or the like in simulation of a cigarette package comprising, a rectangular tubular member, a frame fitting within said tubular member and having opposed end portions serving as ends for said

tubular member, a cigarette simulating element movably mounted in said tubular member, and means located within said tubular member limiting the degree of movement of said element.

3. An ornamental charm for bracelets or the like shaped to simulate a cigarette package comprising, a rectangular tubular member, a frame member mounted within said tubular member and having opposed end portions fitting between the end edges of said tubular member to form a substantially complete and partial closure respectively for the ends of said tubular member, a cigarette simulating element mounted in said tubular member and having a portion movable into position outwardly thereof through the partially closed end of said tubular member.

4. In an ornamental charm, a rectangular tubular casing member having open ends, a frame member telescopingly mounted within said casing member and having opposed end portions fitting within the opposite end edges of said tubular member, means retaining said members against relative movement, a cigarette simulating element movably mounted within said casing member, and means carried by said element and one of said members for limiting the movement of said element relative to said members.

5. In an ornamental bracelet structure a series of connected bracelet links, an ornamental charm shaped to simulate the appearance of a cigarette package and comprising a rectangular tubular member, a frame fitting within the said tubular member and having a portion serving as a closure for one end of said tubular member and a portion serving as a support for a cigarette simulating element, a cigarette simulating element mounted in said tubular member and supported by said frame, and means carried by one of said bracelet links engaging said tubular member for supporting the charm relative to said bracelet.

KARL FASSNACHT.
